[57] CLAIM

The ornamental design for a flexible cooler, as shown and described.

DESCRIPTION

FIG. 1 is a top, left side, perspective view of a flexible cooler of the present design, side portions of a strap and two zipper pulls shown in broken line and forming no part of the first embodiment of the present design;

FIG. 2 is a front elevational view thereof;

FIG. 3 is a rear elevational view thereof;

FIG. 4 is a left side elevational view thereof, a right side view being a mirror image;

FIG. 5 is a top plan view thereof;

FIG. 6 is a bottom plan view thereof; and,

FIG. 7 is a front elevation view of an alternate embodiment of FIG. 1, the difference being the zipper pull cord attached to two spaced apart zipper pulls on the front.
